UNITED STATES PATENT OFFICE.

PHILIP W. MOORE, OF EVANSTON, ILLINOIS. ASSIGNOR TO THE P. & M. CO., OF CHICAGO,
ILLINOIS, A CORPORATION OF ILLINOIS.

ANTICREEPER FOR RAILS.

1,167,587.

Specification of Letters Patent. Patented Jan. 11, 1916.

Application filed July 29, 1912. Serial No. 711,978.

To all whom it may concern:

Be it known that I, PHILIP W. MOORE, a citizen of the United States, residing at Evanston, in the county of Cook and State 5 of Illinois, have invented new and useful Improvements in Anticreepers for Rails, of which the following is a full, clear, concise, and exact description, reference being had to the accompanying drawing, forming a part 10 of this specification.

My invention relates to an anti-creeping device for railway rails.

Among the objects of my invention I aim to provide an improved rail anchor which 15 will effectively grip the rail when applied thereto and which will not loosen or relax its grip thereon when the pressure between the anti-creep and the tie is relaxed; which has a minimum of friction between the interlocking parts of the anti-creep and a maximum of friction between said parts and the rail base gripped thereby; which has a comparatively large angle of sliding engagement for the relatively movable parts of the 20 anti-creep to provide for a "take up", whereby the anti-creep may be applied to rails which vary in width, and which has parts that are positively locked against a movement which would tend to loosen their 25 grip on the rail base, and yet which may be disengaged when desired without breaking or mutilating the locking means.

The rail anchors shown in the accompanying drawings illustrate two embodiments of 30 the invention. Other embodiments may, of course, be devised.

The views of the drawings are as follows:

Figure 1 is a top plan view of a preferred 35 form of rail anchor, the outline of the rail being shown in dotted lines. Fig. 2 is an end elevation thereof, a portion of the rail being shown in sectional elevation. Fig. 3 is an elevation partly in section, taken on the line 3--3 of Fig. 1. Figs. 4, 5 and 6 are 40 respectively a plan view and elevation and partial sectional elevation of a modified form of rail anchor.

The anti-creep or rail anchor shown in 45 Figs. 1, 2 and 3 comprises two relatively movable members having sliding positive engagement with each other along a line somewhat diagonal with respect to the length of the rail. The larger of the two

members 1 may be called the clip and the smaller of the two members 2 may be called 55 the mate. The clip 1 is provided with a rail-gripping jaw 3 which grips one side of the rail base, and the mate 2 is provided with a rail-gripping jaw 4 which grips the other side of the rail base. Either or both 60 jaws may be reinforced by suitable flanges, if desired.

The clip 1 is provided with an under-cut engaging wall 5, along which a corresponding under-cut engaging wall 6 on the mate 2 65 is adapted to slide when the parts are being assembled, and against which said wall 6 abuts firmly when the parts have been driven to their position of final engagement with each other and with the rail base. 70 The mate 2 is received loosely within an outer jaw 7 on the clip 1, said jaw also being suitably reinforced. The clip and the mate as will be seen, have an interlocking wedging engagement beneath the rail base by 75 virtue of the diagonally arranged under-cut walls, consequently, when the parts are assembled loosely on the rail base, and the mate is slid along the rail base within the jaw 7, it is apparent that the mate as a 80 whole moves inward toward the center of the rail until the rail base is gripped between the opposite jaws 3 and 4. The mate is driven into its final position of firm wedging engagement by hammer blows directed 85 preferably against the outer end thereof which is reinforced by a suitable flange 8 adapted to withstand said blows. The clip is provided with a downwardly extending tie-abutting tongue or flange 9, and accordingly is driven firmly against the side of the tie at the same time that the mate is being 90 driven into final position, as the hammer blows against the mate are directed toward the tie.

The mate is provided with a plurality of small bosses or projections 10 which are illustrated as being circular but which may have any desired configuration. When the mate is being driven into the clip, these 100 projections slide freely along beneath the relatively thin wall 11 in which the jaw 7 terminates. After the mate has been driven toward the tie as far as possible, the clip and the mate are then positively locked against 105 a return relative movement by bending

down portions of the thin wall or diaphragm 11, the clip being constructed preferably of malleable iron. In bending down the metal it is not necessary that the operator know just where the bosses are located, as all that is necessary is to direct a few hammer blows back and forth along the wall 11, whereupon whatever portions thereof happen to span two of the bosses 10, will be deflected inwardly. By providing a plurality of bosses an inexperienced or careless operator stands more chance of bending the metal at the right place than might otherwise be the case. Furthermore, if the metal is deflected immediately behind more than one boss, as in Fig. 3, for example, the security of the locking arrangement is correspondingly increased.

It is to be noted that although the mate is almost entirely inclosed by the jaw 7, said jaw performs no direct function in maintaining the parts in wedging engagement, as said engagement takes place entirely beneath the rail base. As a result there is no friction between said mate and said jaw aside from a possible slight friction between the thin wall 11 and the bosses 10 before the metal is bent. There is greater friction, of course, between the interlocking engaging walls 5 and 6, but even this friction is relatively slight compared with the friction developed between the jaws 3 and 4 and the opposite sides of the rail base, as said jaws have to be sprung somewhat when they are applied, and hence they grip the rail base firmly both above and below; furthermore, the bearing surface is of considerable area.

The angle made by the engaging walls 5 and 6 with the longitudinal axis of the rail is relatively great, and consequently the effective width of the rail anchor; that is to say, the space between the jaws 3 and 4 may be varied considerably by sliding the mate in and out of the clip. Accordingly, I am enabled to apply the rail anchor to rails of varying widths, thereby providing the necessary "take up". In this connection it should be noted that even if it is possible to drive the mate only about half way into the clip, as shown in Fig. 1, enough bosses are provided so that there are always one or two beneath the wall or diaphragm 11 in convenient position to lock the parts together when the wall is bent in.

The advantage of providing positive locking means to maintain the parts of the anchor in their most effective position, is well understood. By providing the positive locking means which I have described above, the recognized advantages are attained in a simple and practical manner. If the rail backs up for any reason, the rail anchor as a whole withdraws with the tie, and if the rail subsequently moves forward again, the

bearing face 9 engages the tie and immediately prevents further creeping.

Attention is directed to the fact that in view of the considerable extent of the flexible wall or diaphragm 11, and the fact that it usually spans two abutments when an intermediate portion is deflected, the liability of breaking the same is very small. In certain prior devices locking tongues have been provided which project from one of the elements of the anti-creeper and which are adapted to be bent over at a considerable angle to engage some other part and lock the same against movement. In view of the unnecessarily extreme bending to which these tongues may be subjected, they are apt to break off, or they may also be broken by careless handling prior to the installation of the device. In the present instance, the thin wall 11, which I have provided, is well protected during ordinary handling and requires only slight deflection; hence the liability of breakage is minimized. When said wall is deflected it is bent down into the space between two adjacent projections and the effect is that of bending the metal into a recess in the co-operating member. Accordingly, it is immaterial whether or not the "projections" actually project above the surface or whether the intervening space is depressed below the surface of said member.

In order to unlock the parts where it is desired to remove the rail anchor, it is only necessary to force a cold chisel or some blunt tool beneath the depressed wall so as to tend to straighten out the same and thereby permitting the loosening and removal of said parts.

In the form of rail anchor shown in Figs. 4, 5 and 6, the main elements are substantially the same as those previously described and the same reference characters have been used to indicate corresponding parts. The rear wall 12 of the mate is inclined somewhat from front to rear, whereby the reinforcing flange 13 may be bent downward by hammer blows to prevent a return movement of said mate after the parts have been assembled, said flange being made sufficiently heavy so as to withstand the blows and providing a hammering surface.

It is apparent that, while the locking feature described above as one phase of my invention, is particularly adapted to the anti-creepers illustrated, it is also adapted to anti-creepers of radically different kinds. Accordingly, I do not limit myself to its use in connection with the anti-creepers shown. As far as certain other phases of my invention are concerned, it is apparent that they may all be employed in various different relations. In general, therefore, I do not limit myself to the particular combinations of elements described and shown, but desire to cover within the scope of my invention, suit-

able equivalent means for accomplishing the desired result wherever said means fall within the scope of the appended claims.

What I claim as new and desire to secure 5 by Letters Patent of the United States is:—

1. An anti-creeper for rails comprising a plurality of relatively movable members, one of said members having a thin wall adapted to be bent into a depression in 10 another of said members so as to lock said two members against movement in one direction, said wall extending in the direction of said relative movement whereby it may be deflected in any one of a number of relative 15 positions to effect said locking.

2. An anti-creeper for rails comprising a plurality of members one of which is provided with a projection and another of which is provided with a thin wall arranged 20 adjacent to said projection, whereby said wall may be deflected behind said projection at any one of a number of intermediate points thereon to lock said members against movement in whatever position they may 25 assume.

3. An anti-creeper for rails comprising a plurality of movable parts, a plurality of projections carried by one of said parts and a thin wall carried by another of said parts, 30 said thin wall being arranged to extend over said projections, whereby it may be bent down between two or more of said projections to lock the parts against relative movement.

35 4. An anti-creeper comprising two relatively movable members each having a jaw adapted to grip one side of a rail base, one of said members having a plurality of ridges and the other of said members having a 40 diaphragm adjacent to said ridges and spanning the same, whereby it may be deflected into the space between said ridges.

45 5. An anti-creeper comprising two relatively movable members each having a jaw arranged to grip one side of a rail base when the parts are assembled, one of said members having a tie-abutting flange and having a thin diaphragm adapted to be bent at some intermediate point so as to obstruct 50 the movement of the other of said members.

55 6. An anti-creeper comprising two parts having interlocking wedging engagement beneath the rail base, one of said parts having a thin wall adapted to be deflected into a recess in the other of said parts.

60 7. A rail anchor consisting of two parts having relative movement along a line somewhat diagonal with respect to the length of the rail, one of said parts having a jaw with- 65 in which the other of said parts is received loosely, said jaw terminating in a thin wall which is adapted to be deflected so as to obstruct the movement of said other part within said jaw.

65 8. A rail anchor consisting of two parts

having abutting faces beneath the rail base which engage each other in a plane which intersects the rail base in a diagonal line, the length of said faces being sufficient to permit one of said parts to slide along the 70 other a sufficient distance to cause said parts to approach or recede from each other a considerable amount, whereby said rail anchor may be applied to rails of varying widths, one of said parts having a row of 75 projections thereon, any one of which may act as a stop when engaged by a deflected portion on said other part.

9. An anti-creeper comprising a yoke and a wedging member, said yoke having a rail-gripping jaw at one end and a larger jaw at the other end and having a diagonally arranged slot intermediate said jaws, said wedging member being received within said larger jaw and having a diagonally arranged rib received within said slot and having also a rail-gripping jaw arranged opposite said first rail-gripping jaw, said wedging member being received loosely within said larger jaw, whereby the friction between said parts is confined mainly to the friction developed between said diagonal rib and the wall of said slot, said larger jaw having reinforcing ribs connected by a wall of thin metal which may be deflected to lock 95 said other member within said jaw.

10. A rail anchor comprising relatively movable members each adapted to grip one side of a rail base, one of said members having a depending tie-engaging flange and having oppositely arranged jaws, one of said jaws being arranged to fit over one side of the rail base and the other of said jaws being larger than said first jaw, whereby a clearance is provided between the same and 100 the opposite side of said rail base, said larger jaw terminating in an edge of reduced thickness reinforced at its ends, whereby said edge may be readily deflected at an intermediate point without danger of 105 breaking the same.

11. A rail anchor comprising relatively movable engaging members, one of which is provided with a jaw adapted to fit over one side of a rail base and provided also with a 110 row of projecting bosses.

12. A rail anchor comprising relatively movable engaging members, one of which is provided with a jaw adapted to fit over one side of a rail base and provided also with a 115 projection having a diagonally arranged bearing face, the upper side of said jaw having a series of projections thereon.

13. A rail anchor comprising relatively movable members, one of said members having a tie-abutting flange and having also a jaw which receives one side of the rail base without contacting therewith, the other of said members being adapted to fit loosely within said jaw and having frictional en- 125 130

gagement with said rail base, said members having coöoperating engaging walls adapted to lock said members against separation along a line transverse with respect to the rail but not along a line nearly parallel thereto, the area of engagement of said walls being greater than the area of engagement of said jaw with the portion of said other member received therein, whereby after the parts are assembled, said other member tends

to move with said rail rather than with the first mentioned member when the rail tends to creep.

In witness whereof, I have hereunto subscribed my name in the presence of two witnesses.

PHILIP W. MOORE.

Copies of this patent may be obtained for five cents each, by addressing the "Commissioner of Patents, Washington, D. C."

It is hereby certified that in Letters Patent No. 1,167,587, granted January 11, 1916, upon the application of Philip W. Moore, of Evanston, Illinois, for an improvement in "Anticreepers for Rails," an error appears in the printed specification requiring correction as follows: Page 3, line 49, claim 5, for the word "point" read *portion*; and that the said Letters Patent should be read with this correction therein that the same may conform to the record of the case in the Patent Office.

Signed and sealed this 1st day of February, A. D., 1916.

[SEAL.]

J. T. NEWTON,

Cl. 238-4

Acting Commissioner of Patents.
